UNITED STATES PATENT OFFICE

101,400

DESIGN FOR A COMBINATION COMB, FINGERNAIL FILE, AND NAIL CLEANER

Thomas H. Riley, Chicago, Ill.

Application July 6, 1936, Serial No. 63,651

Term of patent 3½ years

To all whom it may concern:

Be it known that I, Thomas H. Riley, a citizen of the United States of America and a resident of Chicago, in the county of Cook and State of Illinois, have invented a new, original, and ornamental Design for a Combination Comb, Fingernail File, and Nail Cleaner, of which the following is a specification, reference being had to the accompanying drawing, forming a part thereof, and in which:

Fig. 1 is a side elevational view of a combi-

nation comb, fingernail file, and nail cleaner embodying my new design;

Fig. 2 is a top plan view of the same;

Fig. 3 is a sectional view on line 3—3 in Fig. 1;

Fig. 4 is a side elevational view thereof as seen from the side opposite to that shown in Fig. 1.

I claim:

The ornamental design for a combination comb, fingernail file, and nail cleaner as shown.

THOMAS H. RILEY.
